United States Patent Office

Des. 225,533
Patented Dec. 19, 1972

225,533

ELECTRONIC PRINTING CALCULATOR

Mario Bellini, Milan, Italy, assignor to Ing. C. Olivetti
& C., S.p.A., Torino, Italy

Filed Oct. 13, 1970, Ser. No. 25,476

Claims priority, application Italy Apr. 27, 1970

Term of patent 14 years

Int. Cl. D14—02

U.S. Cl. D26—5

FIG. 1

FIG. 2

FIG. 3

FIG. 4

FIG. 1 is a perspective view of the front, top and right side of an electronic printing calculator showing my new design;

FIG. 2 is a perspective view of the rear, top and left side thereof;

FIG. 3 is a front perspective view; and

FIG. 4 is a rear elevational view thereof.

The rectangular area defined in the upper left corner of the right console is a label area.

I claim:

The ornamental design for an electronic printing calculator, as shown.
